(57) CLAIM

The ornamental design for a head wrap, as shown and described.

DESCRIPTION

FIG. 1 is a top right perspective view of a head wrap showing our new design;

FIG. 2 is a top left perspective view thereof;

FIG. 3 is a bottom left perspective view thereof;

FIG. 4 is a front view thereof;

FIG. 5 is a back view thereof;

FIG. 6 is a top view thereof;

FIG. 7 is a bottom view thereof;

FIG. 8 is a left view thereof; and,

FIG. 9 is a right view thereof.

The broken lines illustrate portions of the head wrap that form no part of the claimed design.
